UNITED STATES PATENT OFFICE

2,042,797

METAL STRUCTURE

Abraham Nechin, Chicago, Ill., assignor to Zelda Nechin, Chicago, Ill.

Application September 11, 1931, Serial No. 562,215

17 Claims. (Cl. 189—34)

My invention relates to metal structure adaptable to and interchangeable for various types of construction, and more particularly to floor or side wall construction of a type somewhat similar to that commonly known as battendeck design. The invention especially contemplates a sheet metal sectional flooring construction in which the floor is built up of long and comparatively wide sheet metal trussed units which are arranged to be supported on the cross beams of the ordinary structural framework of buildings, ships or any other structures, or they may be used for side walls. In this invention the trussed units may be arranged to interlock and are laid one at a time on the cross beams until the entire floor section between the beams has been covered, and the interlocked units may then be secured together by welding, if desired, or each unit may be secured to the succeeding one as laid. The portions engaging the beams also may be securely welded thereto, thereby providing a substantially rigid, strong floor construction.

Broadly, the invention comprises interchangeable units which are adaptable for use in construction work in various capacities, such as floor or side wall construction, stairways, stadium seats, or for concrete forms for buildings, dams, etc. The units may be secured together in various relations or removably supported in a manner to facilitate construction work at minimum cost and to provide maximum efficiency.

I also provide a very economical thin sheet metal unit in which a minimum amount of material is used to provide maximum strength and efficiency.

A further important advantage is the provision of units of the character described in which adjacent units may be easily supported in different planes to provide for a desired varying thickness of floor or wall covering or to provide steps.

While the units are usually made of sheet iron or steel, it should be noted that any suitable metal may be used, and while units which are made of very thin sheet steel are of extremely light weight, aluminum or other suitable material may be used if desired.

A distinct advantage of the present invention is the provision of suitable units which may be quickly and easily laid on standard cross beams or directly on walls, and which may be immediately used as a floor over which heavy loads may be moved safely even before the units are secured together or to the cross beams and even before the entire floor is laid. The work of securing the

units together and to the beams may be accomplished at any time and without interfering with the use of the floor by workmen thereon. This is a very noticeable advantage and has reduced the cost of building construction materially.

The present invention also provides a structure wherein the vibratory diaphragm action, or so-called drum action, of the sheet metal forming the unit surface is reduced to a minimum, thereby preventing the noises inherent in certain types of sheet metal floors now in use.

It is also an object of the invention to provide a novel floor construction wherein the individual units will provide great strength and rigidity with a minimum amount of material, and wherein the units when assembled provide suitably aligned means for the attachment of an ordinary ceiling thereto of any suitable type. The units also provide space for heat or sound-proof insulating material therein.

All of the units are made of comparatively thin sheet metal and the scrap metal trimmed from the sheets is used for trussing the units, thus farther reducing the cost to a considerable extent. The invention is especially arranged to provide a unit of sufficient rigidity and strength by the use of very thin material and the scrap therefrom, and arranged to support maximum loads with minimum deflection.

My invention also contemplates an embodiment wherein provision is made for allowing electric wiring, conduits or pipes to be mounted therein and to pass between the floor and the cross beams.

It is also an object to provide a floor construction in which the individual units are easily and conveniently formed and assembled and which may then be laid, to form a complete floor structure, with a minimum amount of labor and expense.

Further objects will be apparent from the specifications and appended drawings.

In the drawings, Figure 1 is a top plan view of a section of flooring illustrating an embodiment of this invention;

Fig. 2 is a transverse sectional perspective view through the flooring and cross beams and taken on a line corresponding to line 2—2 of Figure 1;

Fig. 3 is a fragmentary sectional view similar to that shown in Fig. 2 and illustrates the transverse and longitudinal trussing arrangement used in the individual units;

Fig. 4 is a fragmentary sectional perspective view taken on a line corresponding to line 4—4 of Figure 1, and illustrates the method of sup-

porting the ends of the individual units on the cross beams and securing them thereto, the ends of the units being cut to conform to the shape of the cross beams;

5 Fig. 5 is a detailed front elevation of one of the unit supporting brackets illustrated in Fig. 4, a portion of the unit resting thereon being shown in transverse section;

10 Fig. 6 is a perspective view of one of the interlocking brackets used for securing the units together;

15 Fig. 7 is a transverse sectional view through the floor portion of one of the units and illustrates the formation and longitudinal distortion of the section for the purpose of preventing diaphragm action, the extent of the formation being somewhat exaggerated for purposes of illustration;

Fig. 8 is a transverse sectional view taken through one of the brace or truss members;

20 Fig. 9 is a detailed perspective view illustrating another method of securing the units together;

25 Fig. 10 is a fragmentary perspective view of an embodiment of my invention arranged to provide for conduits or electric wiring to be supported within the contour of the floor structure and to pass over the cross beams;

Fig. 11 is a detailed sectional view illustrating the form of filler or side units used with the embodiment shown in Fig. 10;

30 Fig. 12 is a fragmentary perspective view of another form of interlocking means, and also illustrates the perforations for securing a floor covering to the units;

Fig. 13 is a detailed sectional view illustrating one method of applying floor covering;

Fig. 14 is a detailed sectional view illustrating a slightly modified form of unit construction and method of securing the units together;

40 Fig. 15 is a detailed sectional view illustrating a slightly modified form of truss arrangement;

Fig. 16 illustrates the method of using the units for stairs or for stadium or auditorium stepped floors;

45 Fig. 17 illustrates the unit arrangement for obtaining level floors when used with floor surfacing material of various thickness;

Fig. 18 illustrates a method of using the units for concrete forms;

50 Fig. 19 illustrates a slightly modified form of unit arranged for convenience in nesting for storage or transportation; and

Fig. 20 illustrates an arrangement of units also formed for convenient nesting, one of the flanges being eliminated.

55 Referring to the drawings in detail, the embodiment illustrated comprises a floor structure made up of elongated sheet metal flooring units 1, and filler or side units 2 and 3. These units are supported on the usual rectangularly arranged cross beams 4 and 5, the ends of the units resting on the cross beams 4, and one edge of each of the filler units 2 and 3 resting on one of the cross beams 5. The cross beams may be of the usual I-beam design used in structural iron work.

60 The sections 1 are made of relatively very thin sheet metal, and are formed longitudinally to provide a comparatively wide floor portion 6, and a downwardly extending beam-like web portion 7 having an inwardly turned flange 8 formed thereon. This flange may be used for supporting a ceiling which latter may be attached thereto by any suitable means. The opposite edge of the floor portion 6 is also formed downwardly to pro-

vide a comparatively narrow engaging flange 9 for securing the units together and also to stiffen the individual units.

65 Each of the individual units 1 is provided with brace or truss members 10, 11, and 12, which are secured together and to the member 1, preferably by welding, as illustrated in Figs. 2 and 3, in a manner to provide a suitable transverse stiffening arrangement for all the sections. A plurality of these truss arrangements are used, and they are 10 preferably equally spaced along the length of the individual units.

70 Longitudinal truss members 12^a may be secured at the junction of the members 10, 11, and 12, and to the floor portion at a point midway between the transverse trusses as shown in Fig. 3. While these longitudinal trusses, as well as the vertical truss members 12, may ordinarily be dispensed with they are sometimes found to be desirable where exceptionally heavy loads are to 20 be supported.

75 The filler unit 2 is of similar construction to the units 1, except that the flange 9 is omitted, thereby allowing the floor portion of the unit to rest directly upon one of the longitudinal cross beams 5, as shown in Fig. 2. The filler unit 3 which is used at the opposite side of the floor section from the unit 2 comprises only a floor portion 6^a having a downwardly extending flange 9^a corresponding to the flanges 9 of the other 30 sections. The opposite edge of the floor portion 6^a rests upon the longitudinal cross beam 5, and suitable truss members 13 and 14 are welded together and to the unit 3 in spaced relation in a similar manner to the truss members previously 35 described. Longitudinal truss members 12^a may also be provided if desired as shown in Fig. 3. In order to stiffen the truss members, which are formed from the scrap trimmed from the sheets forming the units, they are preferably formed in 40 an arcuate cross section as shown in Fig. 8.

80 The ends of the units are cut away at 15 to conform to the contour of the I-beams, as illustrated in Fig. 4, and in laying the floor a filler section 2 (Fig. 1) is first placed in position, having its ends resting on the cross beams 4 and its longitudinal floor portion edge resting on one of the cross beams 5. The necessary number of units 1 are then laid in position with their ends resting on the cross beams 4, and the downwardly extending flanges 9 supported and interlocked in suitable brackets 16, one of which is shown in Fig. 6, and which may be spot welded in spaced relation on the downwardly formed web portion 7 of the units as shown in Fig. 6, or 45 pierced and formed from the web portion 7, see Fig. 12.

85 The filler section 3 is then laid, as illustrated in Fig. 2, with its ends resting on the cross beams 4 and the longitudinal edge of its floor portion 6 resting on the cross beam 5. As each section is constructed to provide great strength and as they are all interlocked, the floor may immediately be used and the building construction may continue without loss of time. The flanges 9 may be secured to the brackets 16 at any time, even while the floor is in use if desired, preferably by being welded thereto by electric or other suitable welding means, through the holes 17 in the brackets. As these brackets are spaced across the entire 70 length of each of the units 1 and 2, all of the units are thereby rigidly secured together in one complete floor section.

90 Angle brackets 18 and 19 are welded to the I-beams and to the flanges of the units, as illus-

trated in Fig. 4. These brackets may be welded in position in any suitable manner. In Fig. 5 the bracket 19 is illustrated as being welded at the points A, B, C, and D. It will be understood that all of the brackets 16, 18, and 19 may be bolted in place, if desired, instead of being welded, or the brackets 18 and 19 may be dispensed with and the flanges 9 and 7 may be welded together, or may be bolted as shown in Fig. 9.

During the formation of each unit the floor portion 6 is angularly formed, as shown in Fig. 3. This is a sharp angular formation or scoring on a central longitudinal line 20. In practice, the average width of the individual units is approximately 24 inches, although they may be much wider, and the angular depression or scoring at the longitudinal line 20 is approximately one-eighth inch. The floor portion 6 is formed in a manner similar to that illustrated in Fig. 7, the drawing being somewhat exaggerated for purposes of illustration. This formation or distortion of the floor surface is an important feature of the present invention, in that it effectively prevents buckling of the floor portion and, together with the truss arrangement and securing means, substantially eliminates all of the diaphragm action or so-called drum action of the floor surface.

The ends of the units of adjacent floor sections may be welded together and to the cross beams 4, as shown at 21, and the filler sections are welded together and to the beams 5 at 21^a, thereby providing an integral floor composed of sections, each section being built up of longitudinal units.

In the embodiment illustrated in Fig. 10, the downwardly extending web portion 7 is tapered adjacent each end of the unit and the upwardly extending portion 8^a of the flange 8 is arranged to rest upon the cross-beam 5 in a position to retain the floor portion of the unit in spaced relation to the top of the cross beam to allow electric wiring, conduits or pipes to extend thereunder. The web portion 7 of the unit is also provided with openings 22 to allow pipes or conduits to be extended transversely of the units and between the floor and ceiling.

Fig. 11 illustrates the construction of the fillers or side units for use with the embodiment illustrated in Fig. 10. In this construction, the side unit floor portions are provided with down-turned flanges 23 having openings 24 therein for the passage of pipes or conduits and in-turned flanges 25 for the purpose of stiffening the flanges 23 and supporting the unit on the I-beam.

Fig. 12 illustrates the method of forming interlocking clips 26, corresponding to the clips or brackets 16 shown in Fig. 6, by piercing the web portion 7 of the unit and forming the clips in a position to interlock with and support the downwardly extending flange 9 to retain the units in alignment. In the embodiment illustrated in this figure, the floor portion of each unit is formed to provide a closed U-shaped longitudinal rib 27 which may completely close and spot welded at intervals. This rib, in addition to the angular formation shown in Fig. 7, effectively serves to prevent the drum action as well as to stiffen the floor portion longitudinally, and, in effect, provides a beam-like reinforcement adjacent the apex of the longitudinal distortion of the floor portion. A one piece triangular sheet metal truss 28 may be used if desired instead of the truss members 10, 11, and 12, previously described. The in-turned flange 8 may also be

turned upwardly at 29 to provide longitudinal stiffening, or may be formed to provide any suitable bead. The floor portion may be provided with sheared perforations 30 for securing a floor covering thereon. These perforations are preferably very small and are shown much enlarged in Fig. 12 for purposes of illustration.

The method of securing the floor covering is illustrated in Fig. 13 where the covering E is applied to the floor and engaged in the holes 30. Any suitable floor covering, such as mastic, Flint-kote, gypsum or wood and which may be comparatively thick if desired, is secured to the floor by being pressed snugly on and cemented to the units. Mastic type materials are more securely engaged by the perforations.

In the embodiment shown in Fig. 14, the floor section is provided with similar down-turned web-like flanges 31 on each side and in-turned flanges 32. If desired, alternate units 33 may be provided having short down-turned flanges 33^a. The web 31 of the adjacent unit provides sufficient strength for both units when they are secured together. The units are secured together by means of bolts 34, or may be welded. The bolted construction is sometimes preferable to welding the units as, in the case of temporary buildings, the wrecking cost is considerably less, as the units may be easily taken apart. A slightly modified truss arrangement is provided comprising cross bars 35 which are secured at 36 to the longitudinal truss bars 37. These bars 37 are secured to the junction of the cross bars 35 and to the floor section midway between the cross bars in a manner similar to that shown in Fig. 3.

Fig. 15 illustrates a modified form of truss arrangement in which the ends of a truss 38 are secured to the in-turned flanges 32, the center of the truss being welded or otherwise secured to the floor portion at 39.

Fig. 9 illustrates a method of securing the units, disclosed in Fig. 2, together, by means of bolts 40. These bolts may be used in conjunction with the clips 16, if desired, or the clips may be entirely dispensed with to provide a readily demountable structure. In some cases it is desirable to omit both bolts and clips and spot weld the webs together.

As previously stated, the units are interchangeable and adaptable for various structural uses and may be mounted and secured together in various ways to provide desired variations in floor or side wall or other structure.

It will be noted, that the interlocking clips 16 or 26 may be secured to or formed on the beam-like portion 7 in any desired location, or the web portion 7 may have holes pierced therein in any desired location to receive suitable bolts for securing the units together, and the location of these holes will determine relative positions of adjacent units.

In Fig. 16, the interchangeable units 1 are secured together by means of bolts 41, the bolt holes having been pierced in the flanges in a position to secure the adjacent units in stepped or stair-like relation. It will be understood that the bolt holes may be pierced in a location to provide any desired height or riser. This arrangement is particularly adapted for auditorium or coliseum floor construction where the units may be of any desired width and secured together to provide the desired stepped relation.

It is sometimes desirable to cover a portion of a floor with a thin floor covering, such as linoleum, and adjacent portions with a thicker cover-

ing, such as mastic cement. In order to provide for the variation in thickness of the floor covering, the units are arranged to be interlocked in a relation corresponding to the variation in thickness of the floor coverings. This arrangement is illustrated in Fig. 17 in which a portion of the floor is covered with linoleum, as indicated at 42, and an adjacent portion is covered with a considerably thicker coating of mastic cement or other suitable material 43. By this arrangement, any desired thickness of adjacent floor coverings may be accommodated.

The units are also adaptable for interchangeable use in forming molds for concrete floors or for use in dam construction, or other similar purposes.

Fig. 18 illustrates a method of using the units as forms or molds for concrete floors. The usual method of making these concrete floors is to provide comparatively wide transverse I-beams 44, wooden forms are supported between the I-beams and slightly below their upper surface. These wooden forms are usually supported from the floor below on suitable removable jacks. The construction and removal of these forms in the usual manner requires considerable expense and labor.

The units 1 may be used instead of the wooden forms by mounting them, as illustrated, on suitable jacks or blocks 45 which are in turn supported on the lower flanges of the I-beams 44, or on suitable cross timbers. The units are removable interlocked together by means of the clips, as previously described, and the concrete is poured thereon to provide a desired thickness of floor, suitable concrete reinforcing members usually being supported on the I-beams. As soon as the concrete floor has set, the units are easily removed for further use as desired.

In the usual method of making sheet metal floors, it has been found practically impossible to prevent the vibratory drum action of the metal. The floor portion has also been very irregular and a considerable amount of labor has been necessary in securing the sheet metal in position. It has also been found difficult to provide suitably aligned portions to which ceilings might be attached.

The present invention provides a structure which overcomes substantially all of the difficulties previously experienced, and provides easily mounted interchangeable units in which the floor surface, as well as the ceiling portions, are very rigid and are in accurate alignment, and the units may be easily mounted with a minimum amount of labor and expense.

Careful tests also disclose that the units are materially stronger and will support greater loads without material deflection than previous devices.

This invention also provides a floor structure having greater strength and less weight than those previously used. For convenience in nesting, it is sometimes desirable to form the flange 8 outwardly as shown in Fig. 19. When formed in this manner, the units may be conveniently nested and the truss members are not welded in place until the units are transported to the place where they are to be used.

In the construction shown in Fig. 20, the flange 9 is omitted and the floor portion is offset at 46 to receive the overhanging edge of the adjacent floor portion 6 which may be welded thereto. This method of forming the units also allows convenient nesting and the truss members may

be secured in place, as indicated by the dotted lines, either before or after the floor is laid.

It is obvious that modifications may be made without departing from the spirit of the invention, and I desire to be limited only by the prior art and the appended claims.

Having thus described my invention, what I claim and desire to secure by Letters Patent is:

1. A drum-action proof floor construction for use with spaced floor beams of irregular cross-section, comprising a plurality of elongated sheet metal floor units, downwardly extending flanges on said floor units, said flanges being cut away at their ends to conform substantially to the contour of the cross-beams, the conforming ends 15 of said flanges being rigidly secured to said beams and means for interlocking said flanges, each of the floor units having a longitudinal formation arranged to prevent diaphragm action.

2. A flooring unit comprising a comparatively 20 long and narrow section, L-shaped in cross-section, a plurality of truss means secured adjacent the outer ends of the arms of the L-shaped member and extending therebetween, and means on said unit for interengagement with other units, 25 the floor portion of said unit being longitudinally depressed to prevent diaphragm action.

3. An elongated sheet metal floor unit having a 30 floor surface longitudinally distorted over its entire length to prevent diaphragm action, a comparatively narrow downwardly extending flange on one longitudinal edge of said unit, a comparatively wide downwardly extending flange on the opposite longitudinal edge of said unit and terminating in a comparatively narrow turned 35 flange, and angularly disposed transverse truss members between said flanges and said surface portion.

4. A flooring construction comprising a comparatively long and narrow sheet metal unit providing a floor surface angularly depressed along 40 its longitudinal center line, a short downturned flange on one side, a long downturned and in-turned flange on the opposite side, a brace secured adjacent said short flange and adjacent the lower 45 end of said long flange, a short brace secured adjacent the center of said long brace and adjacent the top of said long flange, and a post secured adjacent the intersection of said braces and to the underside of said unit adjacent its 50 depressed longitudinal line.

5. Interchangeable units of the character described comprising elongated sheet metal members having central, longitudinal, angular depressions extending from the center to the sides 55 of said members, the edges of said members being provided with downwardly extending longitudinal flanges and means cooperating with said flanges to secure said units together in stepped relation.

6. A floor comprising a plurality of elongated sheet metal units having central longitudinal depressions, extending from the center to the sides of said members, longitudinal flanges on said 65 units, means associated with said flanges and arranged to secure the units together in stepped relation, and floor coverings of different thickness secured to said units to provide an aligned floor surface.

7. A drum-action proof floor structure of the character described comprising a plurality of thin, elongated sheet metal floor portions supported at their ends and secured together in parallel alignment, each having a slightly depressed 75

obtuse angular floor surface with the apex substantially on the longitudinal axial line of the surface.

8. A sheet metal unit for the purpose described comprising a sheet metal floor portion having a comparatively slight central longitudinal depressed portion extending from the center to the sides of said floor portion for preventing diaphragm action, longitudinal stiffening means, and transverse truss means.

9. A sheet metal unit for the purpose described comprising a sheet metal floor portion having a comparatively slight central longitudinal depressed portion extending from the center to the sides of said floor portion for preventing diaphragm action, longitudinal stiffening means, transverse truss means, and inter-engaging means for securing said units together to form a floor.

10. An interchangeable unit of the character described comprising an elongated sheet metal member, each member being longitudinally scored adjacent its center line with the portions on each side slanting slightly upwardly to the sides thereof for preventing diaphragm action, transverse truss means for said units, and means for securing said units together to form a floor.

11. A unitary floor structure of the character described comprising elongated sheet metal floor units supported at their ends, each having a slightly depressed obtuse angular floor surface with the apex substantially on the longitudinal axial line of the unit, said units being formed to provide a floor portion having a long downwardly-extending longitudinal flange on one side and a short longitudinal flange on the other side, and means on said long flanges for interlocking adjacent short flanges thereto with the floor surfaces of adjacent units in alignment.

12. A unitary floor structure of the character described comprising elongated sheet metal floor units supported at their ends, each having a slightly depressed obtuse angular floor surface with the apex substantially on the longitudinal axial line of the unit, said units being formed to provide a floor portion having a long downwardly-extending longitudinal flange on one side, a short longitudinal flange on the other side, means on said long flanges for interlocking adjacent short flanges thereto with the floor surfaces of adjacent units in alignment, and transverse truss means between said flanges.

13. A unitary floor structure of the character described comprising elongated sheet metal floor units, each having a slightly depressed obtuse

angular floor surface with the apex substantially on the longitudinal axial line of the unit, said units being formed to provide a floor portion having a long downwardly-extending longitudinal flange on one side and a short longitudinal flange on the other side, means on one of said flanges for interlocking with a flange on an adjacent unit with their floor surfaces in alignment, and transverse stiffening means on said unit.

14. A unitary floor structure comprising a plurality of elongated sheet metal floor members supported at their ends and each formed to provide a floor portion having a slightly depressed obtuse angular floor surface with the apex substantially on the longitudinal axial line of the unit, a downwardly-extending longitudinal flange on each side, and transverse stiffening means, the flanges of adjacent members being welded together to form a unitary drum-action proof floor structure.

15. A unitary floor structure comprising a plurality of elongated sheet metal floor members supported at their ends and each formed to provide a floor portion having a slightly depressed obtuse angular floor surface with the apex substantially on the longitudinal axial line of the unit, a downwardly-extending longitudinal flange on each side, and transverse stiffening means, the flanges of adjacent members being rigidly secured together to form a unitary drum-action proof floor structure.

16. A unitary floor structure comprising a plurality of elongated sheet metal floor members supported at their ends and each formed to provide a floor portion having a slightly depressed obtuse angular floor surface with the apex substantially on the longitudinal axial line of the unit, a downwardly-extending longitudinal flange on each side, transverse stiffening means, the flanges of adjacent members being welded together to form a unitary drum-action proof floor structure, and interengaging means for maintaining said members in surface alignment before and while being welded.

17. A sheet metal unit for the purpose described comprising a sheet metal floor portion having a comparatively slight longitudinal depressed portion extending from the center toward the sides of said floor portion for preventing diaphragm action, longitudinal stiffening means and transverse truss means, said floor portion being perforated to retain a floor covering.

ABRAHAM NECHIN. 55
